PUMP ATTACHMENT FOR INTERNAL COMBUSTION MOTORS

Filed March 23, 1933

UNITED STATES PATENT OFFICE

1,951,279

PUMP ATTACHMENT FOR INTERNAL
COMBUSTION MOTORS

John Goodwin, Washington, D. C.

Application March 23, 1933, Serial No. 662,363

15 Claims. (Cl. 123—198)

This invention relates to apparatus for use with internal combustion motors whereby one or more motor cylinders may be readily converted to permit their use for the compression or pumping of air. It is the principal object of the invention to provide a device of this character which may replace the conventional spark plug and which will function either for ignition purposes or for air compression without the removal of any parts, so that if desired the device may be more or less permanently associated with the motor.

Thus in the preferred form of the invention the device may consist of a complete unit embodying an ignition means, not differing materially from the conventional spark plug, and valve controlled passages for introducing air into the cylinder and permitting discharge of air therefrom. It is a feature of the invention that the passages in question are placed in communication with the cylinder by simple manipulation of the ignition means without removal of the latter, the construction being such that when communication is thus effected the ignition current is necessarily interrupted. By this arrangement the possibility of firing any charge which might be drawn into the cylinder while it is acting as a pump is eliminated.

It is a further object of the invention to provide a device of this character in which the resistance to flow of air into the cylinder is reduced to a minimum, whereby substantially pure air free of combustible mixture will be drawn into the cylinder and discharged therefrom.

It is a further object of the invention to provide a pump attachment for internal combustion motor cylinders employing an ignition means adapted to seat within the cylinder head in such manner that the two electrodes occupy the conventional position with respect to the combustion chamber, one of these electrodes being movably supported with respect to the other whereby the gap between the electrodes may be increased to such an extent as to prevent firing, the displacement of the movable electrode serving to place the combustion chamber in direct communication with air inlet and discharge passages in the pump attachment.

Further objects and features of the invention will be apparent from the following description taken in connection with the accompanying drawing, in which:

Figure 1 is a sectional view taken substantially on the axis of an internal combustion motor cylinder and illustrating one form of pump attach-

ment, the disposition of the parts being such that the cylinder may function normally; and

Figure 2 is a fragmentary sectional view illustrating the relative position of the parts when the cylinder is used for pumping air.

In order to facilitate an understanding of the invention, the device selected for the purpose of illustrating the invention is described specifically herein. It will be understood, however, that no limitation of the scope of the invention is thereby intended and that various alterations are contemplated such as fall within the underlying principles of the invention.

Referring more specifically to the drawing, it will be observed that a conventional internal combustion motor cylinder 10 is illustrated, the cylinder being provided with the usual water jacket 11 and a piston 12 reciprocating in the cylinder. The cylinder is also provided with the usual threaded opening 14 adapted to receive the conventional spark plug. In the application of my invention the spark plug is removed from one or more of the motor cylinders and is replaced by the device shown in the drawing, this device preferably comprising a member 15 having a threaded tubular extension 16 at the lower end thereof, the latter being receivable within the spark plug opening 14. Cooperating electrodes 18 and 19 are provided, the latter extending through an insulating element 21, preferably of porcelain, and having a conducting bushing 22 secured to its upper end, this bushing being adapted to receive the usual cooperating contact member on the ignition wire. The element 21 is in turn received within a sleeve 24 which is threaded in an opening 25 extending through the member 15. A nut 27 is threaded in the sleeve 24 and engages the insulating element 21 to retain the latter in any desired position as shown in the drawing. The lower end of the sleeve 24 is adapted to seat against an annular shoulder 28 to close the lower portion 26 of the opening 25, a gasket 30 being preferably employed to prevent leakage of the products of combustion.

It will be observed from the construction thus far described that the device is formed and functions identically with the conventional spark plug when the parts occupy the position in which they are shown in Figure 1 of the drawing, the electrodes 18 and 19 extending within or to a point adjacent to the combustion chamber so that the main portion of the combustion charge may be directly ignited.

The member 15 is further provided with an air inlet passage 32 and an air outlet passage 33.

these passages merging at their lower ends with the opening 25. When the sleeve 24 occupies the position shown in Figure 1 of the drawing, communication between the passages 32 and 33 5 and the opening 26 is interrupted and the passages thus perform no function. If, however, the sleeve 24 be partially withdrawn by threading the same outwardly, the passages 32 and 33 will both be placed in direct communication with the opening 25 and with the combustion chamber of the cylinder. At the same time the electrodes 18 and 19 will be separated to an extent sufficient to prevent discharge of ignition current therebetween. The sleeve 24 is preferably withdrawn 10 to an extent sufficient to completely open the passages 32 and 33 and may be locked in this partially withdrawn position by means of a nut 34 which is threaded on the exterior of the sleeve 24 and which may be turned down into engagement 15 with an annular shoulder 35 surrounding the opening 25.

Check valves are preferably provided in each of the passages 32 and 33, these valves functioning to prevent movement of air in opposite directions in the two passages. Thus the valve in the passage 32 may comprise a ball 37 normally resting on a plurality of inwardly extending fins 38 in the passage 32 to permit air to pass freely in a downward direction through the passage and into 20 the combustion chamber of the cylinder. A sleeve 40 is threaded within the outer end of the passage 32 as indicated at 41, this sleeve being preferably formed to provide a small chamber 42 having a plurality of apertures 43 therein of such 25 size as to prevent the movement into the passage 32 of large foreign bodies. The sleeve 40 is further provided with an annular face 45 on which the ball 37 is adapted to seat when air is being expelled from the combustion chamber, the air 30 pressure forcing the ball into seating position.

The check valve in the passage 33 is illustrated as comprising a ball 48, the latter being normally retained in engagement with an annular seat 49 so as to prevent movement of air through the 35 passage 33 into the combustion chamber. Preferably a coil spring 50 is provided to retain the ball in the position shown in the drawing, this spring reacting against an annular shoulder 52 formed on the interior of a sleeve 53 which is 40 threaded into the outer end of the passage 33 as indicated at 54. The sleeve 53 is also provided with means whereby connection with a conduit or 45 hose will be effected, for instance the outer end of the sleeve may be threaded as shown at 55 to receive a coupling member.

The operation of the device will be apparent from the foregoing description. When one or more of the spark plugs in a motor are replaced by the device as described hereinbefore, the sleeve 24 is first threaded inwardly to the position shown 50 in Figure 1 of the drawing so that the device performs the function of the conventional spark plug, the passages 32 and 33 being isolated from the combustion chamber. Thus the motor may 55 be started in the usual manner with all cylinders functioning and may operate normally until it is desired to utilize the motor for the pumping of air. When such use is required, the sleeve 24 is turned to partially withdraw the same to place 60 the passages 32 and 33 in communication with the opening 25, the nut 34 being turned down to lock the sleeve in position. Such cylinders as 65 are now functioning normally will continue to operate, effecting reciprocation of the piston 12 70 within the cylinder 10. On the downward or

suction stroke air will be drawn into the chamber 42, through the passage 32 about the ball valve 37, and through the opening 25 into the combustion chamber. On the upward or compression stroke of the piston this air will be discharged through the passage 33, forcing the ball 48 outwardly in the passage against the action of the coil spring 50 and discharging through the hose or conduit coupled at the outer end of the 80 passage.

When it is desired to discontinue the use of the device as an air compressor, the nut 34 may be loosened and the sleeve 24 turned to the position in which it is shown in Figure 1 of the drawing without stopping the motor, and the cylinder automatically resumes its normal function, the electrodes 18 and 19 being again placed in operative relationship and the cylinder head being sealed.

It will be observed that as the result of the very direct connection between the inlet and outlet passages and the cylinder a maximum quantity of air is drawn into the cylinder on each suction stroke and a maximum volume expelled on each compression stroke of the piston. The resistance 100 to flow of air through the inlet passage is so small as compared with the resistance offered to the flow of combustible mixture into the cylinder that no appreciable quantity of combustible charge will be introduced. It will be appreciated 105 that the partial vacuum established in the intake manifold by reason of the operation of the remaining cylinders also tends to reduce the quantity of combustible mixture supplied to the cylinder when the device is functioning as a pump.

The device may be either coupled directly to apparatus operable by compressed air, for instance a paint spray, or may be delivered to a supply tank if more uniform pressure is desired.

The invention finds its most important use in 110 motor repair shops where a supply of compressed air is essential in various operations, such as painting or inflation of tires, and since an automobile motor is always available in such shops the expense of installing and maintaining a separate pumping unit can be eliminated.

Having thus described the invention, what is claimed as new and desired to be secured by Letters Patent is:

1. In a device for use with internal combustion motors, the combination with a member having a tubular portion threaded for reception in a spark plug opening and having air inlet and outlet passages communicating with the interior of said tubular portion, of ignition means supported in said member, said ignition means comprising an electrode formed on said tubular portion, and an electrode movable into and out of operative relationship with said first named electrode, and means associated with said second electrode for interrupting communication between said passages and the tubular portion of said member when said second electrode is moved into operative relation with said first electrode.

2. In apparatus for use with internal combustion motors, the combination with a member having air inlet and outlet passages therein and an opening communicating with both of said passages, of ignition means supported within said member for movement into a position in which communication between said passages and said opening is interrupted, and into a position in which communication is afforded between said passages and said opening and said ignition means is rendered inoperative.

3. In apparatus for use with internal combustion motors, the combination with a member having air inlet and outlet passages therein and an opening communicating with both of said passages, of ignition means supported within said member for movement into a position in which communication between said passages and said opening is interrupted, and into a position in which communication is afforded between said passages and said opening and said ignition means is rendered inoperative, and means for locking said ignition means in said last named position. 80
4. In apparatus for use with internal combustion motors, the combination with a member having air inlet and outlet passages therein and an opening communicating with both of said passages, of ignition means supported within said member for movement into a position in which communication between said passages and said opening is interrupted, and into a position in which communication is afforded between said passages and said opening and said ignition means is rendered inoperative, and one-way valves associated with each of said passages. 85
5. In a device for use with internal combustion motors, the combination with a member having a tubular portion threaded for reception in a spark plug opening and having air inlet and outlet passages communicating with the interior of said tubular portion, of ignition means supported in said member, said ignition means comprising an electrode formed on said tubular portion, and an electrode movable into and out of operative relationship with said first named electrode, means associated with said second electrode for interrupting communication between said passages and the tubular portion of said member when said second electrode is moved into operative relation with said first electrode, and means for locking said second electrode in inoperative position. 90
6. In a combined spark plug and pump attachment for internal combustion motors, the combination with a pump chamber having air inlet and outlet passages, said chamber being receivable in a spark plug opening to place said passages in communication with a motor cylinder, a fixed electrode carried by said chamber, and a displaceable electrode supported for movement to two positions in which said electrodes are in operative relation and out of operative relation respectively, and means associated with said displaceable electrode and movable therewith to interrupt communication between said passages and the motor cylinder when said electrodes are placed in operative relation. 95
7. In a combined spark plug and pump attachment for internal combustion motors, the combination with a pump chamber having air inlet and outlet passages, said chamber being receivable in a spark plug opening to place said passages in communication with a motor cylinder, a fixed electrode carried by said chamber, and a displaceable electrode supported for movement to two positions in which said electrodes are in operative relation and out of operative relation respectively, said electrodes extending within the motor cylinder when in operative relation, and means associated with said displaceable electrode and movable therewith to interrupt communication between said passages and the motor cylinder when said electrodes are placed in operative relation. 100
8. In apparatus of the class described, the combination with a pump chamber having air inlet and discharge openings, said chamber being receivable in the spark plug opening of an internal combustion motor to place said openings in communication with the motor cylinder, of displaceable ignition means movably supported in said chamber, said ignition means being movable therein to a position in which the same is rendered operative for ignition purposes and communication between said openings and cylinder is interrupted, or to a position in which the same is rendered inoperative for ignition purposes and communication between said openings and cylinder is established. 105
9. In apparatus of the class described, the combination with a pump chamber having air inlet and discharge openings, said chamber being receivable in the spark plug opening of an internal combustion motor to place said openings in communication with the motor cylinder, of displaceable ignition means movably supported in said chamber, said ignition means being movable therein to a position in which the same is rendered operative for ignition purposes and communication between said openings and cylinder is interrupted, or to a position in which the same is rendered inoperative for ignition purposes and communication between said openings and cylinder is established. 110
10. In a combined spark plug and pump attachment for motor vehicles, the combination with a pump chamber having a tubular extension receivable in the spark plug opening of an internal combustion engine, said chamber having a passage aligned with said tubular extension, of ignition means supported for movement within said passage and extension, and separate substantially straight air inlet and outlet passages intersecting said first named passage adjacent said extension. 115
11. In a combined spark plug and pump attachment for motor vehicles, the combination with a pump chamber having a tubular extension receivable in the spark plug opening of an internal combustion engine, said chamber having a passage aligned with said tubular extension, of ignition means supported for movement within said passage and extension, separate substantially straight air inlet and outlet passages intersecting said first named passage adjacent said extension, said inlet and outlet passages forming an acute angle with said first named passage, and check valves disposed in said inlet and outlet passages. 120
12. In a combined spark plug and pump attachment for motor vehicles, the combination with a pump chamber having a tubular extension receivable in the spark plug opening of an internal combustion engine, said chamber having a passage aligned with said tubular extension, of ignition means supported for movement within said passage and extension, separate substantially straight air inlet and outlet passages intersecting said first named passage adjacent said extension, said inlet and outlet passages forming an acute angle with said first named passage, and check valves disposed in said inlet and outlet passages, said ignition means being displaceable to a position in which all of said passages are blocked or to a position in which open communication is afforded between said passages. 125
13. In a combined spark plug and pump attachment for motor vehicles, the combination 130
- 75 8. In apparatus of the class described, the

- with a pump chamber having a tubular extension receivable in the spark plug opening of an internal combustion engine, said chamber having a passage aligned with said tubular extension, of an electrode supported for movement within said passage and extension, separate substantially straight air inlet and outlet passages intersecting said first named passage adjacent said extension, said inlet and outlet passages forming an acute angle with said first named passage, check valves disposed in said inlet and outlet passages, and a spring in said outlet passage for urging said check valve to closed position. 80
- 10 an acute angle with said first named passage, check valves disposed in said inlet and outlet passages, said electrode being displaceable to a position in which all of said passages are blocked or to a position in which open communication is afforded between said passages, and a fixed electrode associated with said tubular extension, said fixed electrode being disposed for cooperation with said first named electrode only when the latter occupies the passage blocking position. 85
- 15 14. In a combined spark plug and pump attachment for motor vehicles, the combination with a pump chamber having a tubular extension receivable in the spark plug opening of an internal combustion engine, said chamber having a passage aligned with said tubular extension, of ignition means supported for movement within said passage and extension, separate substantially straight air inlet and outlet passages intersecting said first named passage adjacent said extension, said inlet and outlet passages forming an acute angle with said first named passage, check valves disposed in said inlet and outlet passages, and a lock nut associated with said ignition means for retaining the latter against unintentional displacement from either position. 90
- 20 14. In a combined spark plug and pump attachment for motor vehicles, the combination with a pump chamber having a tubular extension receivable in the spark plug opening of an internal combustion engine, said chamber having a passage aligned with said tubular extension, of ignition means supported for movement within 95
